UNITED STATES PATENT OFFICE.

HIRAM P. BARNES, OF LAPORTE, INDIANA.

ELECTRICAL RESISTANCE.

1,318,128.

Specification of Letters Patent.

Patented Oct. 7, 1919.

Application filed June 9, 1917. Serial No. 173,907.

To all whom it may concern:

Be it known that I, HIRAM P. BARNES, a citizen of the United States, and a resident of the city of Laporte, county of Laporte, and State of Indiana, have invented certain new and useful Improvements in Electrical Resistances, of which the following is a specification.

My invention relates to improvements in lighting systems especially adapted for use on automobiles in "dimming" the headlights thereof.

The invention consists in the combinations and arrangements of parts hereinafter described and claimed.

The invention will be best understood by reference to the accompanying drawings forming a part of this specification, and in which,

20 Figure 1 is a diagrammatic view of a lighting system embodying my invention, and

Fig. 2, an enlarged detail view of a resistance box employed in the system.

25 The preferred form of construction as illustrated in the drawings, comprises a resistance box or casing 3 having perforated lugs 4 thereon for mounting the same on the dashboard, or other convenient location, of

30 an ordinary automobile. The resistance box 3 is provided with opposed binding posts 5, 6, 7, 8, 9 and 10 connected by resistance coils

11, 12, 13, 14 and 15 within box 3. A double-throw switch 16 is also installed in the system, the movable arm 17 of said switch being connected by means of a wire 18 with the socket or other connection 19 leading to the usual magneto or other source of current for the lighting system. One of the points

40 20 of the switch 16 is connected by means of a wire 21 with the ordinary headlights 22 on the automobile, the other terminals of said lights being grounded as indicated.

The other point 23 of the switch 16 is connected by means of a wire 24 with one of the binding posts 6, 7, 8, 9 or 10 as desired, the other binding post 5 being connected by wire 25 with the wire 21 and thence with the lights 22.

50 By this arrangement, it will be observed that when the switch arm 17 is thrown into contact with the switch point 20, the circuit is direct from the socket 19 through the

lights 22 to the ground, thus exciting said lights with their full brilliancy. However, 55 when the switch arm 17 is thrown into connection with the other switch point 23, the circuit from the socket 19 is through one or more of the resistance coils in the resistance box 3, thence through the lights 22 to the 60 ground. The resistance thus introduced into the circuit, serves to "dim" the lights 22 and thus reduce their brilliancy to render their use unobjectionable in meeting or passing pedestrians or other vehicles. By shifting 65 the wire 24 to one or the other of the binding posts 6, 7, 8, 9 or 10, more or less resistance may be employed and the device readily adjusted to different systems as desired. When the switch arm 17 is thrown to central 70 or neutral position, the lights are out.

While I have illustrated and described the preferred form of construction for carrying my invention into effect, this is capable of variation and modification without 75 departing from the spirit of the invention. I, therefore, do not wish to be limited to the precise details of construction set forth, but desire to avail myself of such variations and modifications as come within the scope of 80 the appended claim.

Having described my invention what I claim as new and desire to secure by Letters Patent is:

A variable resistance for electric lighting 85 systems comprising a casing; two sets of three binding posts each on opposite walls of said casing arranged in transversely alining pairs; a resistance coil extending between the members of each pair of binding posts; an intermediate resistance coil extending from the end binding post on one side of the casing to the intermediate binding post on the other side of the casing; and a second intermediate resistance coil extending from the opposite intermediate binding post to the end binding post on the opposite side of said casing, substantially as described.

In testimony whereof I have signed my 100 name to this specification in the presence of two subscribing witnesses.

HIRAM P. BARNES.
